DESIGN FOR A GOLF BAG CART

William Quiring, Wichita, Kans., assignor to
Quiring-Owston, Inc., Wichita, Kans., a corporation of Kansas

Application August 24, 1945, Serial No. 121,618

Term of patent 14 years

(Cl. D14—3)

To all whom it may concern:

Be it known that I, William Quiring, a citizen of the United States, residing at Wichita, in the county of Sedgwick and State of Kansas, have invented a new, original, and ornamental Design for a Golf Bag Cart, of which the following is a specification, reference being had to the accompanying drawing, forming a part thereof.

The single figure in the drawing is a perspective view of a golf bag cart, showing my new design.

I claim:

The ornamental design for a golf bag cart, as shown.

WILLIAM QUIRING.
